(57) **CLAIM**

(21) Appl. No.: **29/241,316**

The ornamental design for the speaker and image producing device, as shown and described.

(22) Filed: **Oct. 27, 2005**

DESCRIPTION

(30) **Foreign Application Priority Data**

Apr. 27, 2005 (KR) 30-2005-0013997

FIG. 1 is a perspective view of the speaker and image producing device showing my design;

(51) **LOC (8) Cl.** **14-01**

FIG. 2 is a front view thereof;

(52) **U.S. Cl.** **D14/168; D14/136**

FIG. 3 is a rear view thereof;

(58) **Field of Classification Search** D14/135–136, D14/156, 167–168, 204, 207, 491, 229, 496; 381/300–302, 261–364; 181/144–151; D6/511–512; 369/75.11, 75.21, 77.21, 77.11; 720/612, 720/619, 647, 655; 455/344, 347–351

FIG. 4 is a left side view thereof;

See application file for complete search history.

FIG. 5 is a right side view thereof;

(56) **References Cited**

FIG. 6 is a top plan view thereof;

U.S. PATENT DOCUMENTS

FIG. 7 is a bottom plan view thereof; and,

D222,269 S * 10/1971 Gibson D14/229

FIG. 8 is a perspective view thereof showing a compact disc suspended for insertion and illumination. The broken line showing is for illustrative purposes only and forms no part of the claimed design.
